(57) **CLAIM**

The ornamental design for a dispenser base, as shown and described.

DESCRIPTION

FIG. 1 is a top perspective view of a dispenser base showing my new design;

FIG. 2 is a front view thereof;

FIG. 3 is a rear view thereof;

FIG. 4 is a left side view thereof;

FIG. 5 is a right-side view thereof;

FIG. 6 is a top view thereof;

FIG. 7 is a bottom view thereof; and,

FIG. 8 is an environmental in use perspective view thereof showing positioned beverage dispenser and glasses.

The broken lines in the drawing depict environmental subject matter only and form no part of the claimed design.
